The ornamental design for a product holding and dispensing bag, as shown and described.

DESCRIPTION

FIG. 1 is a perspective view of the product holding and dispensing bag in accordance with my new design, shown in the filled condition and in the dispensing position on an inclined plane, represented in broken lines which does not form part of the claimed design;

FIG. 2 is a front plan view thereof;

FIG. 3 is a top view thereof;

FIG. 4 is a rear plan view thereof;

FIG. 5 is a bottom view thereof;

FIG. 6 is a left side elevational view thereof;

FIG. 7 is a right side elevational view thereof;

FIG. 8 is a plan view thereof, similar to FIG. 2, but shown in an un-filled condition; and,

FIG. 9 is a plan view similar to FIG. 8 in which the bottom left and right hand portions have been separated and removed along the perforation line indicated in FIGS. 2, 4, and 8, for completeness of illustration.
